UNITED STATES PATENT OFFICE.

ADOLF H. SCHAFFERT, OF YOUNGSTOWN, OHIO, ASSIGNOR TO THE GENERAL FIRE-PROOFING COMPANY, OF YOUNGSTOWN, OHIO, A CORPORATION OF OHIO.

DRAWER SUSPENSION FOR FURNITURE.

1,178,877.

Specification of Letters Patent. Patented Apr. 11, 1916.

Application filed March 31, 1915. Serial No. 18,348.

To all whom it may concern:

Be it known that I, ADOLF H. SCHAFFERT, a citizen of the United States, residing at Youngstown, in the county of Mahoning and State of Ohio, have invented 5 certain new and useful Improvements in Drawer Suspension for Furniture, of which the following is a specification.

This invention relates to an improved 10 suspension or drawer fitting having special utility in its application to metal furniture, and more particularly to sliding drawers of cases or cabinets adapted for filing and storing documents.

15 A primary object of the invention is to provide a novel and practical type of drawer suspension, operating on a different principle from the ordinary extension slides, and which provide for properly supporting the 20 drawer as it is moved to varying positions within or without the casing or cabinet. In this connection, the invention has specially in view a form of attachment and construction which will entirely take the place of 25 telescopic extension slides and equivalent devices which are ordinarily employed for slidably supporting drawers within their casings. In this aspect, the invention obviates the disadvantages of the usual drawer 30 suspensions which require a considerable number of pieces in order to insure the satisfactory operation of the drawer, thereby lessening the possibility of parts becoming 35 inoperative or out of order while at the same time effecting a great economy from a manufacturing standpoint.

40 A further object of the invention is to provide a drawer suspension or fitting which will not only subserve every function of the ordinary telescopic or equivalent slides with respect to the proper support and guiding of the drawer in the variable 45 positions which the latter occupies as it is moved into and out of its casing, but which will also permit a full depth of the drawer to the casing without any loss of filing space. 50 Also the improved construction is specially applicable to metal furniture because it provides a construction which is not affected by uneven surfaces or defects that may result 55 from the operation of dies in bending and shaping the metal parts. Irrespective of such defects which seriously interfere with the operation of some forms of construction, the present device provides a novel combi-

nation and arrangement of parts which positively insures a free and easy movement of the drawer in and out of the casing without binding of parts or jerkiness of movement, and wherein frictional resistance is reduced 60 to a minimum.

With these and other objects in view which will more readily appear as the nature of the invention is better understood, the same consists in the novel construction, 65 combination, and arrangement of parts hereinafter more fully described, illustrated and claimed.

The essential features of the invention involved in carrying forward the idea of entirely dispensing with telescopic or equivalent members, the invention is necessarily susceptible of structural modification without departing from the spirit or scope thereof, but a preferred and practical embodiment thereof is shown in the accompanying drawings, in which—

Figure 1 is a vertical central longitudinal sectional view of one unit of a metal cabinet illustrating the improved drawer suspension or fitting applied to one drawer and its casing. Fig. 2 is a similar view showing the drawer slightly extended with the folding extension slide partly engaged with the rear upwardly extending deflecting section of the track member. Fig. 3 is a vertical cross sectional view on the line 3—3 of Fig. 2. Fig. 4 is a detail skeleton view illustrating the folding extension slide lying in its horizontal position and acting strictly as an extension slide for supporting and guiding the drawer as it is drawn out of the casing. Fig. 5 is a detail fragmentary perspective view of the folding extension slide, showing the same lifted and illustrating its pivotal attachment to the drawer. Fig. 6 is an enlarged detail sectional view on the line 6—6 of Fig. 5, illustrating a preferable form of roller bearing guide roller employed at the rear ends of the folding extension slides.

Like reference characters designate corresponding parts throughout the several figures of the drawings.

The application of the present invention requires no special structural change or alteration in the drawer or its casing, so for illustrative purposes there is shown in the drawings one unit of a metal filing case or cabinet which includes a suitably construct-

ed drawer casing 1 and the sliding drawer 2 operating therein.

According to the present invention, the drawer casing 1 has rigidly secured to the opposite inner sides thereof fixed guiding and supporting track members which may be offset from the casing walls by bracket plates 3, though this is not an essential detail of the invention. The said fixed track members preferably consist of channel plates having upper and lower flanges 4 and 5 and the intermediate connecting web portion 6, thus forming at the inner sides of the track members a guideway or channel 15 to accommodate certain parts of the device as will presently appear. Each of these channelled track members includes a main horizontal track section A and a rear upwardly extending deflecting track section B. 20 The track section B is of the same channel formation as the track section A, and the channels or grooves of said two track sections are in direct communication and continuation, one with the other. But, it 25 will be observed that the rear track section B is disposed within the rear end portion of the drawer casing and curves rearwardly and upwardly from the rear end of the main horizontal section A to a point approaching the top of the casing to provide 30 means for folding or deflecting to an out-of-the-way position the extension slide attachment to the drawer.

The extension slide attachment referred 35 to has been termed a folding extension slide, because it is lifted or folded out of the way when the drawer is moved inward toward its closed position. It is designated generally, in Fig. 5 of the drawings, by the reference letter S and preferably comprises a 40 slide-frame consisting of a pair of opposite extension bars 7 and a connecting tie rod or equivalent connector 8 between the rear end portions of said bars. This forms a 45 frame structure capable of rising and falling to provide the folding effect for the extension slide, and in order that this feature of the invention may be satisfactorily accomplished the opposite side extension bars 50 7 are pivotally united at their forward ends as at 9, to opposite side portions of the drawer 2 preferably at a point intermediate the front and rear ends of the drawer.

The pivotal connection between the extension bars 7 and the sides of the drawer may 55 be provided for in any suitable manner, preferably by a riveting operation, and in this connection it will be further noted that the preferable form of the invention involves welding or otherwise attaching to the outer bottom corner portions of the drawer reinforcing angle plates 10, the lower flanges 11 of which engage within the horizontal track section A over the lower flanges 5 thereof. The said lower flanges

11 of said reinforcing plates 10 also constitute stops to limit the lowermost position of the extension bars 7, which latter bars are also of an angle formation with their flanges 12 disposed above the upper flanges 4 of the fixed track members. 70

At the fixed location of the pivots 9 for the front ends of the bars 7 there are arranged, at the outer sides of the latter, retainer projections or buttons 13 which operate within the channels of the fixed track members and assist in holding the drawer in operative relation to the track members. This function also applies to the rear revolving guide and guide rollers 14 which 75 are suitably mounted upon the outside of the bars 7 at the rear ends thereof. To reduce the frictional resistance to a minimum, the rollers 14 are preferably of a roller-bearing or ball-bearing type, as clearly 80 shown in Fig. 6 of the drawings. In this figure of the drawings, the rollers 14 are shown as of flanged formation loosely mounted upon the shank of a headed pin 15 between which and the roller body is formed 90 a race for the bearing rolls or balls 16.

The rear guide rollers 14 operate within the channels or guideways of both track members A and B, and the forward movement of the drawer is limited by the engagement of stop projections 15^a at an intermediate point on the bar 7, with stationary stop projections 16^a arranged in an interfering position at the front extremities of the horizontal track sections A, as best seen 100 in Figs. 2 and 4 of the drawings.

From the construction described, it will be observed that the extension slide S permits the drawer to be drawn out of the casing for its full length, as well as partially, and in any extended position will be supported and held by the extension slide S. Upon the inward movement of the drawer, the rear guide rollers 14 enter the rear track sections B and are deflected upwardly 110 thereby, with the result of causing the extension slide S to swing upwardly and over the rear end portion of the drawer so as to be entirely out of the way of the latter being carried at its rear end to the extreme 115 back of the casing, thus conserving the full depth of the casing for filing or storage purposes. While these desirable functions are performed, the extension slide S also gives a free and easy opening and closing movement for the drawer since the pressure of the load is substantially divided between the rollers 14 of the slide and the front supporting rollers 17 mounted within the front portion of the casing adjacent 120 the drawer opening and engaged by the flange of the angle plate 10 which thereby 125 in effect acts as a track member on the drawer in addition to its reinforcing function. 130

From the foregoing, it is thought that the construction and advantages of the invention will be readily apparent without further description.

5 I claim:

1. A drawer support including, in combination with the sliding drawer and its casing, track members mounted on said casing and having upwardly directed rear extensions, and a swinging extension slide pivotally carried by the sides of the drawer and engaging the track members and their rear extensions.

10 2. A drawer support including, in combination with the sliding drawer and its casing, track members mounted on its casing, and having rear upwardly curved extensions, and a swinging extension slide pivotally carried by the sides of the drawer at an intermediate point thereof and engaging the track members.

15 3. A drawer support including in combination with a sliding drawer and its casing, track members fitted to the casing and having rear upward extensions, and an extension slide pivoted adjacent the bottom edge of the drawer at an intermediate point thereof and having elements engaged and guided by the track members and their extensions.

20 4. A drawer support including in combination with a sliding drawer and its casing, track members fitted to the casing and having rear upward extensions, and an extension slide comprising opposite connected bars pivoted adjacent the lower side edges of the drawer at an intermediate point thereof and carrying roller elements engaged and guided by the track members and their extensions.

25 5. A drawer support including in combination with a sliding drawer and its casing, channeled track members fitted to the casing and having rear upward extensions, and an extension slide comprising opposite connected bars pivoted at their forward ends to opposite sides of the drawer and carrying at their rear ends roller elements which operate in the channels of the track members and their extensions.

30 6. A drawer support including in combination with a sliding drawer and its casing, channeled track members fitted to the casing and having rear upward extensions, angle bars fitted to the bottom corners of the drawer, an extension slide comprising opposite connected angle bars pivoted at their forward ends to said angle bars on the

35 drawer and carrying at their rear ends roller elements operating in the channels of the track members and their extensions, retaining elements projecting outward from the pivoted ends of said angle bars of the slide and operating in the channels of the track members, and supporting rollers located at the front of the casing and engaged by the angle bars on the drawer.

40 7. A drawer support including, in combination with a sliding drawer and its casing, a horizontal track mounted on said casing and having upwardly directed rear end portions, an extension slide comprising opposite rigid bars pivoted at one end to the sides of the drawer, means carried by the free end portions of the bars for riding in the horizontal track and upwardly directed end portions thereof, and stops carried by the drawer for engaging the rigid bars of the slide to support the drawer when the same is pulled out of the casing.

45 8. A drawer support including, in combination with a sliding drawer and its casing, a horizontal track mounted on said casing and having upwardly directed grooved rear end portions, an extension slide comprising opposite rigid bars pivoted at one end to the sides of the drawer adjacent the lower edge thereof, means located at the pivot point of said bars for traveling in the horizontal track, and means carried by the free end portions of the bars for riding in said horizontal track and upwardly directed grooved rear end portions thereof.

50 9. A drawer support including, in combination with a sliding drawer and its casing, a horizontal track mounted on said casing and having upwardly directed grooved rear end portions, an extension slide comprising opposite rigid bars pivoted at one end to the sides of the drawer adjacent the lower edge thereof, means located at the pivot point of said bars for traveling in the horizontal track, means carried by the free end portions of the bars for riding in said horizontal track and upwardly directed grooved rear end portions thereof, and stop flanges carried by the drawer for engaging the rigid bars of the slide to support the drawer when the same is pulled entirely out of the casing.

55 In testimony whereof, I hereunto affix my signature in the presence of two witnesses.

ADOLF H. SCHAFFERT.
